UNITED STATES PATENT OFFICE.

ANDREW M. MORRISON, OF DUBUQUE, IOWA, ASSIGNOR TO MORRISON AND KRETSCHMER MANUFACTURING COMPANY, OF DUBUQUE, IOWA, A CORPORATION OF IOWA.

WATER-CLOSET.

No. 888,636.

Specification of Letters Patent.

Patented May 26, 1908.

Application filed November 6, 1907. Serial No. 400,995.

To all whom it may concern:

Be it known that I, ANDREW M. MORRISON, a citizen of the United States, residing at Dubuque, in the county of Dubuque and State of Iowa, have invented certain new and useful Improvements in Water-Closets, of which the following is a specification.

My invention relates to water closets with special reference to the means for securing the seat and cover to the bowl, and the object is to provide a simple, graceful, strong and inexpensive hinge or attachment of the seat and cover on the bowl whereby the seat or cover will have no laterally shifting movement but when opened or closed will always describe the same arc of a circle.

It consists essentially in bolting to the cover two straps each having two arms and each arm provided with an opening near its end through which opening the arms of the straps are pivoted upon a rod or bar common to both. Between the arms of each of the straps upon the same bar are pivoted bent lugs which project beneath the seat and to which the seat is rigidly bolted; and further consists in pivoting to the same bar between the arms of each straps seat posts by which the whole is rigidly bolted to the seat-shelf of the bowl.

The following specification will point out in detail the manner of construction and mode of operation when read in connection with the accompanying drawings forming a part hereof in which:

Figure 1 is a perspective view of my device taken from the rear, showing the different parts attached. Fig. 2 is a perspective view of one of the cover posts. Fig. 3 is a perspective view of one of the double arm straps. Fig. 4 is a side view of one of the lugs for pivotally attaching the seat. Fig. 5 is a bottom view of Fig. 4. Fig. 6 is a side view of the hinge.

Like characters of reference denote corresponding parts in each of the figures.

Referring to the drawings, 2 designates the bowl, 4 the seat and 5 the cover. Against the under side of the cover near its opposite edges are bolted straps 6 by screw threaded bolts 8 cast integral with the straps provided with nuts 7 which nuts consist of a cap 9 having thereon a channel for engagement with a screw-driver to operate it, or the head may be made square and be operated by a wrench or other tool, and a cup 11. This

cup is provided with a screw threaded opening adapted to engage the threads on the bolt 8 and be screwed thereon. In this manner of securing the straps 6 to the cover it will have a finished appearance especially where the straps 6 and the caps 9 are nickel or silver plated. These straps 6 are each slightly bent and terminate in two arms 10 and are provided near their outer ends with openings 12 through which they are each pivoted upon a bar 14 extending in a horizontal plane at about the middle of the seat 4. Against the under side of the seat 4 is secured a lug 15 near opposite edges on the same side of the seat. These lugs are each provided with bolts constructed the same as bolts 8 and provided with a nut similar to those for securing the straps 6 to the cover. They are also provided with openings 18 through which they are each pivoted upon the bar 14 between the arms 10 of the strap 6 and by this means the seat is pivotally secured to the bar 14.

In the shelf 20 of the bowl 2 are two openings through which the seat posts 22 shown in Fig. 2 pass and are held to the shelf 20 by the nuts 24 on their lower ends. The upper ends of the posts are each provided with an opening 26 through which it is pivoted upon the bar 14 between the arms 10 of the strap 6. These posts hold the cover and seat firmly upon the bowl. Upon each outer end of the bar 14 are nuts 28 which, when tightened against the outer arms 10 of the strap 6, will prevent the cover from any lateral motion and when it is raised or lowered it will always describe the same arc of a circle and since the seat is also pivoted between these arms there will be no lateral or side shifting movement of the seat.

It is manifest that the two arms 10 of the straps 6 may be transferred to the posts, and the straps have a single arm and pivoted with the lugs between the arms of the post or the lugs be provided with the two arms and the straps and posts be pivoted between the arms of the lugs, the essential feature being to have either one of the three provided with two arms and the other two provided each with a single arm and pivoted between the arms of the third.

It will be seen by the pivoting of the posts and the lugs between the arms 10 of the strap 6 that when the cover is thrown back it will contact on the inner shoulders of the

arms with the posts and prevent any further backward movement and thus hold it in an inclined position and by the peculiar shape and bend of the lugs 15 the seat may be 5 turned back to an incline with the cover. Further it will be observed that by constructing the straps and lugs with integral bolts and providing the cup-shaped nuts that the covers and seats will be rigidly 10 bolted thereon and be prevented from any lateral movement and will present an exceedingly finished appearance.

Having now described my invention what I claim is:

- 15 1. In combination with a bowl, a seat and cover of a water-closet, a bar, straps secured in the same plane to the opposite edges of the cover and each having two arms provided with openings in their outer ends through 20 which they are pivoted upon said bar, lugs bolted upon the underside of the seat near its opposite edges and bent at an angle to the seat and pivoted to said bar between the arms of the straps, and a seat post bolted to 25 the shelf of the bowl near each side in the rear of the bowl and pivoted to the bar between the arms of the coöperating strap, all combined substantially as shown.
2. In a device of the character described 30 and in combination with a bowl, a seat and cover, a bar, straps secured to the same side

of the cover near its opposite edges by bolts integral with said straps and provided with cup-shaped nuts said straps each terminating in two arms having openings there-through by which they are pivoted upon said bar, lugs bolted to the underside of the seat near its opposite edges by bolts integral with the lugs and pivoted to said bar between the arms of said straps, a seat post bolted to 35 the shelf of the bowl near each side in the rear of the bowl and pivoted to said bar between the arms of the coöperating strap, and a nut at each end of the bar adapted to engage the outer sides of the arms of the strap 40 and secure the cover, and seat against any lateral movement on the bowl.

3. In a device of the character described, a bar, straps each provided with two arms pivoted to said bar, lugs pivoted on the bar between the arms of the straps and secured to the seat by bolts, and seat posts pivoted to said bar between the arms of the straps and bolted to the bowl, as and for the purposes shown.

In testimony whereof I affix my signature, in presence of two witnesses.

ANDREW M. MORRISON
